UNITED STATES PATENT OFFICE.

EDWARD E. ASHLEY, JR., OF NOROTON, CONNECTICUT, ASSIGNOR TO WALKER BROTHERS, OF PHILADELPHIA, PENNSYLVANIA, A CORPORATION OF PENNSYLVANIA.

ELECTRICAL WIRING SYSTEM.

Original No. 1,536,748, dated May 5, 1925, Serial No. 686,141, filed January 14, 1924, and in Canada August 18, 1925. Application for reissue filed September 11, 1928. Serial No. 305,255.

My invention relates to a system of electrical wiring for office or other buildings, hotels, factories, apartment houses, residences, etc., and relates more particularly to a system of concealed wiring disposed in conduits located in the walls or partitions of the buildings, and more particularly in the floors.

In accordance with my invention, the main or supply circuit conductors of lighting, power, telephone, signaling or other circuits are disposed in one or more conduits, while the branch or consumption circuit conductors, extending to the points of connection of the electric lights, power devices, telephone instruments, signals, etc., are disposed in a conduit or conduits, the main or supply and branch or consumption circuit conduits being disposed either in the same plane in a wall or floor, or in different planes, and preferably 15 extend transversely to each other at right angles or any other convenient or suitable angle, the conduit or conduits of the main or supply and consumption or branch circuits meeting in a wall or floor box structure in different 20 planes or at different levels, where connections are effected between the main or supply circuit conductors and the branch or consumption circuit conductors.

Further in accordance with my invention, 30 I provide wall or floor box structure, which, if desired, may be made in sections, providing in different planes or at different levels passages or channels extending transversely to each other with suitable opening or openings 35 between the different sections or levels to permit connection of main and branch circuit conductors to each other within the box structure, the conduits of the main and branch circuits communicating with the aforesaid passages or channels.

My invention resides in the system and apparatus of the character hereinafter described and claimed.

For an illustration of one of various forms 45 my invention may take, reference is to be had to the accompanying drawings, in which:

Fig. 1 is a vertical sectional view, partly in elevation, of a box structure and associated conduits embodying my invention.

Fig. 2 is a vertical sectional view, partly in elevation, taken at right angles to Fig. 1.

Fig. 3 is a vertical sectional view, partly in elevation, of a conduit with applied outlet structure.

Fig. 4 is a top plan view, on smaller scale, 55 of the structure shown in Figs. 1 and 2, with the cover removed.

Fig. 5 is a top plan view of the structure shown in Fig. 4 with the parts surmounting the upper box section removed.

Fig. 6 is a top plan view of the lower box section.

Fig. 7 is a top plan view of the member surmounting the upper box section.

Fig. 8 is a bottom plan view of the member 65 shown in Fig. 7.

Fig. 9 is a bottom plan view of the cover holding ring which surmounts the member shown in Fig. 7.

Fig. 10 is a vertical sectional view, partly in 70 elevation, of the floor box in position in a recess in a stratum of the floor.

Fig. 11 is a fragmentary plan view of a system embodying my invention.

Referring to the drawings, the floor box is 75 illustrated as made of superposed sections and comprises the lower metallic section 1, preferably rectangular, surmounted by the upper or second metallic section 2, preferably rectangular. The section 1, shown in plan in Fig. 6, is open at its top and comprises the side walls 3, bottom 4, and the parallel transversely extending partition walls 5 forming within the lower section or box 1 the parallel transversely extending passages or channels 6, 7 85 and 8.

In the example illustrated, there are provided three passages or channels 6, though it will be understood that a greater or lesser number may be employed, as occasion may 90 require.

Communicating with the passage 6 is the metal or other conduit or pipe 9, suitably secured to the side walls 3, as by the nut 10 threaded on the conduit 9 on the exterior of the box section 1, and the conduit bushing 11 threaded upon the conduit on the inside of the box section 1. Similarly, the conduits 12 and 13 communicate, respectively, with the passages or channels 7 and 8, and are similarly secured to the walls 3 of the box section 1. The upper box or box section 2 has the side walls 14 and bottom 15, the latter resting upon the upper edge of the box section 1, the downwardly depending flange 16 on the section 2 embracing or receiving the upper end of the box section 1. The partition walls 17 extend transversely of the box section 2, divid-

ing it into the three channels or passages 18, 19 and 20, the walls 17 and the passages 18, 19 and 20 extending preferably transversely of the partitions 5 and passages 6, 7 and 8 of the lower box section 1, though it will be understood that if suitable or desirable, the passages and partitions of the upper box section may extend parallel with those of the lower box section.

10 In the bottom 15 of the upper box section there is provided the opening 21, in the passage 18, thereby affording communication between the passage 18 of the upper box section and the passage 6 of the lower box section. Similarly, in the bottom 15, in passage 19, is formed the opening 22, affording communication between the passage 19 of the upper box section and the passage 7 of the lower box section. Similarly, in the bottom 15 is provided the aperture 23 in channel 20 to afford communication with the channel 8 of the lower box section.

15 At opposite ends of each of the passages 18, 19 and 20 of the upper box section 2, which is open at its top, are provided the side inwardly extending ribs or flanges 24 and the upstanding bottom flanges or ribs 25, spaced from which are the similar ribs or flanges 26 and 27.

20 Surmounting the upper box section 2 is the member 28, having along two of its opposite sides the downwardly depending flanges 29 embracing the upper end of the box 2.

25 Adjacent its ends the member 28 is provided with elongated recesses or channels 30 adjacent the ribs 31, which are disposed substantially in the plane of the ribs 24 and 25 on the box section 2. The channels 30 are in registry with the spaces or chambers 32 in the box member 2, between the ribs 24 and 25 on the one hand, and 26 and 27 on the other hand. The rectangular conduits 33, 34 and 35 extend through the opening formed by the ribs or flanges 26, 27 and cover member 28 into the chambers 32, and abut against the ribs or flanges 24, 25 and 31. Threaded through the member 28 are the pointed screws 36 engaging the conduits 33, 34 and 35 and grounding the metallic box structure to them. In the chambers 32, around the conduits 33, 34 and 35 may be applied any suitable cement 37 for holding the conduits in place.

30 Bolts or screws 38 extend through the lugs 39 upon the member 28, through the lugs 40 on the box member 2, and thread into the lugs 41 upon the box section 1, whereby the members 1, 2 and 28 are securely held or clamped to each other.

35 The member 28 has the circular opening 42, through which access is had to the three passages or channels 18, 19 and 20 of the upper box section 2. Surrounding the opening 42 is the annular flange 43, spaced from

which is the annular flange 44, between 65 which is formed the annular channel or trough 45, into which projects the annular flange 46 of the cover-holding member 47 having the circular opening 48 disposed above the opening 42 in the member 28. The member 47 has the annular lug 49 and the upstanding annular flange 50. In the bosses 51 are threaded pins or screws 52, which rest upon the bottom of the trough 45 in the member 28, adjustment of the screws serving to level or adjust the member 47 with respect to the floor surface. When the cover is in place on the box, the bosses 51 on the member 47 fit into suitable enlargements 75 formed in the channel 45 (Fig. 7) thus holding the cover against movement in the plane of the floor. The circular cover disk or member 53 fits within the flange 50 of the member 47 and rests upon its annular lug 49, and is secured in position by screws 54 80 threaded into the lugs 55 on member 47, the upper surface of the cover 53 being preferably flush with the upper surface 56 of the floor.

85 In the conduits 9, 12 and 13 may be disposed the main or supply circuit conductors, and in the conduits 33, 34 and 35 may be disposed the branch or consumption circuit conductors. Or in some one or more of the conduits 9, 12, 13 may be disposed consumption or branch circuit conductors, and in some one or more of the conduits 33, 34 and 35 may be disposed main or supply circuit conductors.

90 Generally, however, in the conduits at the higher level, such as conduits 33, 34 and 35, will be disposed the branch or consumption circuit conductors, and outlets therefrom may be effected by any suitable means, as for example, the nipples 57, Figs. 2 and 3, 105 threaded into or otherwise secured to the conduits 33, 34 and 35. Threaded upon the nipple 57 is the bushing 58, which may be adjusted to come flush with the floor surface 56 by rotating bushing 58 upon nipple 57. 110 Threaded into the bushing 58 is the closing member or plug 59, whose upper surface is preferably flush with the floor surface 56.

95 As indicated in Figs. 1 and 2, the floor box, comprising members 1 and 2, may rest upon an unfinished or more or less rough surface 60 of an unfinished floor. For example, 120 may be the upper surface of a cement, concrete, tile or other floor, or substratum of a floor. The screws 52 or some of them are then adjusted to bring the outer faces of the flange 50 and cover plate 53 to a level position corresponding with the level 56 of the floor when finished. With the floor box so in position, and with the main and branch conduits connected thereto, there may be filled in upon the substratum of the floor concrete, cement or other suitable material which 125

flows around the box structure, the conduits, and members 28 and 47, embedding them and holding them in position.

As indicated in Fig. 10, in some cases the 5 substratum 60 of the floor may be cut away to form a recess 61, upon whose bottom 62 the floor box may rest. In such case it may be necessary or desirable to bend the main conduits, as 9, 12 and 13, upwardly, as indicated in Fig. 10, to clear the normal upper surface 60 of the lower floor stratum.

As indicated in Fig. 11, there may be laid out over a floor or unfinished floor of a building a network of main and branch conduits, 15 with the floor boxes disposed at their intersections, and the outlet devices, such as 58 having the closing plugs 59, are distributed along the conduits 33, 34 and 35 at predetermined intervals, or located in the positions in which it is previously known that outlets must be had. Then the floor may be finished, as above described, by applying concrete, cement or other material embedding the conduits and the floor boxes.

25 By way of example merely, it may be assumed that through the main conduits 9 extend conductors carrying current for electric lights. The branch lighting circuit conductors will then be disposed in the conduits 33. To carry the electric lighting current to any suitable place the cover 53 of the appropriate floor box is removed, thereby effecting access through the opening 48 to the channel 18 of the box section 2. The 35 plug 59 of the appropriate outlet is removed, and the branch circuit conductors inserted through the opening into the conduit 33 and fished therethrough to the channel 18 of the upper box section 2 of the floor box, where 40 they are then connected with the supply circuit conductors in the channel 6 of the bottom box section 1, the opening 21 affording access to the supply circuit conductors for making the connections.

45 Similarly, through a suitable outlet communicating with the conduit 34 telephone conductors may be fished therethrough to the channel 19 of the appropriate floor box and connections then made through the opening 22 with the main telephone conductors in the conduit 12. Similarly, from a suitable outlet the conductors of an office signal circuit, as a buzzer circuit, may be passed through the outlet and through the conduit 50 35 to the channel 20 of the upper box section of the appropriate floor box and connections then extended through the opening 23 into the channel 8 of the lower box section 1, in which are disposed the main circuit conductors extending through the conduit 13.

60 What I claim is:

1. An electrical wiring system comprising a network of main and branch circuit conduits disposed in a wall, boxes in said wall 65 at which the main and branch circuit con-

duits meet, each of said boxes having passages disposed in different planes, said main and branch circuit conduits communicating with said passages in different planes, and means for effecting within the box communication between passages in different planes 70 therein.

2. An electrical wiring system comprising a network of main and branch circuit conduits disposed in different planes in a wall, 75 boxes in said wall at which the main and branch circuit conduits meet, each of said boxes having passages disposed in different planes, said main and branch circuit conduits communicating with said passages 80 in different planes, and means for effecting within the box communication between passages in different planes therein.

3. The combination with a box structure having a plurality of parallel channels extending across the box in each of a plurality of different levels respectively, conduits connected with said box structure and communicating, respectively, with different channels, and means within said box structure 85 effecting communication between the channels in one level and the channels in another level.

4. The combination with a box structure having a plurality of parallel channels extending across the box in each of a plurality of different levels, the channels in one level extending transversely to the channels in another level, conduits connected with said box structure and communicating, respectively, 95 with the different channels, and means within said box structure effecting communication between the channels in one level and the channels in another level.

5. The combination with a box structure 105 having a plurality of channels in each of a plurality of different levels, the channels in one level extending transversely to the channels in another level, conduits connecting with said box at different levels and communicating with said channels and means within said box structure effecting communication between the channels in one level and the channels in another level.

6. Conduit-connecting box structure comprising superposed box sections each having 110 a channel, the channels in the different sections extending transversely to each other, said channels in the different sections at their intersection communicating with each other.

7. Conduit-connecting box structure comprising superposed box sections each having a plurality of channels disposed side by side, the channels in one of said sections extending transversely to the channels in another of said sections, each channel of one section communicating with a channel of the other section at their intersection.

8. Conduit-connecting box structure comprising superposed box sections each having 120

a channel, the channels in the different sections extending transversely to each other, said channels in the different sections at their intersection communicating with each other, 5 and a pair of conduit sections connecting with opposite ends of each channel and communicating with each other through said channel.

9. Conduit-connecting box structure comprising superposed box sections each having 10 a plurality of channels disposed side by side, the channels in one of said sections extending transversely to the channels in another of said sections, each channel of one section communicating with a channel of the other section at their intersection, and a pair of conduit sections connecting with opposite ends of each channel and communicating with each other through said channel. 15

10. Conduit-connecting box structure comprising a box section open at its top and having 20 a channel, a second box section having a bottom superposed upon said first section and having a channel extending transversely to the channel in said first section, said bottom 25 of said second section having an aperture effecting communication between said channels in the different sections at their intersection.

11. Conduit-connecting box structure comprising a box section open at its top and having 30 a channel, a second box section having a bottom superposed upon said first section and having a channel extending transversely to the channel in said first section, said bottom 35 of said second section having an aperture effecting communication between said channels in the different sections at their intersection, and a pair of conduit sections connecting with opposite ends of each channel and communicating with each other through 40 said channel.

12. Conduit-connecting box structure comprising a box section open at its top and having 45 a plurality of channels disposed side by side, a second box section having a bottom superposed upon said first section and having a plurality of channels disposed side by side, said bottom of said second section having 50 apertures effecting communication between said channels in the different sections.

50 13. Conduit-connecting box structure comprising a box section open at its top and having 55 a plurality of channels disposed side by side, a second box section having a bottom superposed upon said first section and having a plurality of channels disposed side by side and extending transversely to the channels in said first section, said bottom of said 60 second section having apertures effecting communication between said channels in the different sections at their intersections.

14. Conduit-connecting box structure comprising a box section open at its top and having 65 a plurality of channels disposed side by side, a second box section having a bottom superposed upon said first section and hav-

ing a plurality of channels disposed side by side, said bottom of said second section having apertures effecting communication between said channels in the different sections, and a pair of conduit sections connecting with 70 opposite ends of each channel and communicating with each other through said channel.

15. Conduit-connecting box structure comprising a box section open at its top and having 75 a plurality of channels disposed side by side, a second box section having a bottom superposed upon said first section and having a plurality of channels disposed side by side and extending transversely to the channels 80 in said first section, said bottom of said second section having apertures effecting communication between said channels in the different sections at their intersections, and a pair of conduit sections connecting with opposite ends of each channel and communicating with each other through said channel. 85

16. Conduit-connecting box structure comprising a box section open at its top and having 90 a plurality of channels disposed side by side, a second box section open at its top and having a bottom superposed upon said first section and having a plurality of channels disposed side by side, said bottom of said second section having apertures effecting 95 communication between said channels in the different sections, and cover structure for said second box section having an opening affording access to said channels of said second box section and through said apertures in said 100 bottom to the channels in said first box section.

17. An electrical wiring system comprising main and branch circuit conduits disposed in a wall, a box in said wall at which 105 said main and branch circuit conduits meet, said box having a pair of parallel passages disposed in each of different levels and communicating respectively with said main and branch circuit conduits the passages in each 110 level extending across the box in that level, and means within said box effecting division between passages in the same and different levels and having an opening for communication between a passage in one level and a 115 passage in another level for effecting within the box connections between the main and branch circuit conductors.

18. An electrical wiring system comprising main and branch circuit conduits disposed in a wall, a box in said wall at which 120 said main and branch circuit conduits meet, said box having a pair of parallel passages disposed in each of different levels the passages in each level extending across the box 125 in that level and communicating respectively with said main and branch circuit conduits, means within said box effecting division between passages in the same and different levels and having an opening for communication be- 130

5 between a passage in one level and a passage in another level for effecting within the box connections between the main and branch circuit conductors, a wall outlet communicating with the branch circuit conduits, and the level of the passages communicating with said branch circuit conduits being disposed adjacent said wall outlet.

19. Wall box structure for a concealed conduit electrical wiring system comprising structure forming a pair of parallel passages in each of different levels, said passages being open at their opposite ends in opposite sides of said box structure, said passages extending 10 across the box in their respective levels and being adapted to communicate with conduits at their said opposite ends, and means within said wall box structure effecting communication between a passage in one level and a 15 passage in another level.

20. Wall box structure for a concealed conduit electrical wiring system comprising structure forming a pair of parallel passages in each of different levels, said passages extending across the box in their respective 25 levels and being open at their opposite ends in opposite sides of said box structure and extending transversely to each other and adapted to communicate with conduits at 30 their opposite ends, and means within said wall box structure effecting communication between a passage in one level and a passage in another level.

21. An underfloor wiring system for a plurality of electric services of different characters, comprising a plurality of groups of conduits, each group accommodating the conductors of one character of electric service, the conduits of each group extending transversely of each other, and box structure at 35 which the conduits of the several groups meet, said box structure having a plurality of separate parallel passages in each of different levels, the passages in the different levels 40 extending transversely of each other and extending completely through said box in their respective levels, conduits of the different groups connecting, respectively, with the passages in one level, and the remaining conduits 45 of said groups connecting, respectively, with the passages in the other level, and the transversely extending passages for each group of conduits communicating with each other within said box.

55 22. An underfloor wiring system for a plurality of electric services of different characters, comprising a plurality of substantially parallel conduits for accommodating, respectively, the conductors of the different 60 characters of service, a plurality of boxes spaced from each other longitudinally of said conduits, means forming a plurality of separate parallel passages in each box extending completely therethrough and connecting with said conduits on opposite sides of said box,

and at each of said boxes a plurality of transversely extending conduits for accommodating, respectively, conductors of said different characters of service, means in each of said boxes forming independent transverse 70 parallel passages extending completely through said box and disposed in a level different from said first named passages and connecting, respectively, with said transversely extending conduits, and means in each of said boxes providing communication between those passages in different levels which are associated with the conduits for one of said characters of service.

23. In an underfloor wiring system, box 80 structure having a plurality of parallel channels in each of a plurality of different levels, said channels in the different levels extending transversely to each other and completely through said box in their respective 85 levels, conduits connected with said box structure and communicating, respectively, with the different channels in the different levels, a channel in one level communicating with a channel in the other level, and a single opening 90 in said box structure through which is afforded access to all the channels in the highest level.

24. A connecting box comprising a pair of superposed box members, partition walls in 95 each member forming passages extending transversely through the member to openings in the side walls of the member, a cover member mounted on the top of the upper box member, this cover closing the tops of the 100 passages in the upper box member, the tops of the passages in the lower member being closed by the bottom of upper member, and a removable portion forming part of the cover and serving as a closure through which access 105 may be had to the passages in the upper member, the bottom of said upper member having openings through which access may be had to the passages in the lower box member.

25. A connecting box comprising a pair 110 of superposed box members, partition walls in both members forming passages extending transversely through the members to openings in the side walls of the members, and a cover member mounted on top of the upper 115 member and provided with a removable cover, the member and cover closing the tops of the passages in the upper member, the tops of the passages in the lower member being closed by the bottom of the upper member, and the bottom of the upper member having openings by which access may be had between the passages in the upper and lower members.

26. A connecting box structure comprising a lower box member having partition 125 walls forming transverse passages, openings in the walls of the box through which access is had to these passages, the passages being open at the top, a second box member superposed on the first and having a bottom clos- 130

ing the tops of the passages, partition walls in the second box member defining open top passages in the said member, openings in the wall of the member communicating with the 5 passages, and a cover structure mounted on top of the second box member and closing the tops of the passages therein.

27. A conduit connecting box structure, comprising side and bottom walls, partition 10 members within the structure defining upper and lower parallel passages through the structure the upper passages extending transverse to the lower passages, the upper passages having open tops, openings in the opposite side walls affording access to each of the 15 passages, and a cover member forming the top of the upper passages, this cover member having an opening through which access is had to the interior of the box structure.

28. A conduit connecting box structure, comprising bottom and side walls, openings arranged in oppositely disposed pairs in the side walls, partition members within the structure defining parallel passages connecting pairs of opposite openings, the passages being arranged in transversely extending groups, the groups lying in different levels and means at the openings for receiving and supporting the ends of conduits in communication with the passages through the openings.

29. A conduit connecting box structure, comprising bottom and side walls having openings arranged in pairs in the opposite side walls, partition members within the structure providing separate parallel passages connecting opposite openings, certain of these passages extending transversely to each other with the passages connecting opposite pairs of openings lying in the same level, with the upper passages open at the top, means in the side walls of the structure for receiving and supporting the ends of conduits, each conduit being in communication with a passage through an opening, and a cover structure for closing the tops of the upper passages, certain of the transversely extending passages being in communication with each other within the structure.

30. In a connecting box for wiring ducts, a cover member for the body of the box having an opening defined by spaced flanges, a removable cover having a peripheral flange adapted to be received between said spaced flanges, and means carried by said peripheral flange and entering the space between said spaced flanges for adjusting the level of the cover top.

31. In a connecting box for wiring ducts, 60 a cover member for the body of the box having an opening defined by spaced flanges, a removable cover having a peripheral flange adapted to be received between said spaced flanges, and a plurality of members mounted 65 for adjustment in the edge of said depending

flange and adapted to rest on said cover member between said spaced flanges.

32. In a connecting box for wiring ducts, a cover member for the body of the box having an opening defined by spaced flanges, a 70 removable cover having a peripheral flange adapted to be received between said spaced flanges, and a plurality of bosses on said peripheral flange adapted to be received in recesses in said spaced flanges to hold said 75 cover against movement in the plane of the top thereof.

33. A connecting box comprising a body having openings in its walls, the body having at least eight openings disposed in pairs 80 with the openings of each pair lying in alignment across the box with openings of another pair, partition walls within the box defining pairs of enclosed passages extending across the box, each passage connecting one opening with its aligned opening, the passages of one pair crossing the passages of the other pair in different levels, and means in the walls for supporting the ends of conduits in communication through a pair of openings with passages, whereby conductors in a pair of conduits leading to a pair of adjacent openings in the body wall may pass in separate passages across the box and extend into conduits leading to the opposed openings, these conductors also being kept separate within the box from conductors in the passages which they cross.

34. A connecting box comprising a body having openings in its walls, the body having 100 at least eight openings disposed in pairs with the openings of each pair lying in alignment across the box with openings of another pair, partition walls within the box defining a plurality of enclosed passages, each opening 105 in the wall being connected by one of said passages to its opposed opening, the passages lying in parallel pairs with the passages of one pair crossing those of the other pair in different levels, means in the walls for supporting the ends of conduits in communication through a pair of openings with passages, and means in the partitions through which access may be had between a passage 110 extending in one direction and a passage extending in the other direction.

35. A connecting box comprising a body having openings in its walls, the body having at least eight openings disposed in pairs 120 with the openings of each pair lying in alignment across the box with openings of another pair, partition walls within the box defining a plurality of enclosed passages, each opening in the wall being connected by one of said passages to its opposed opening, the 125 passages lying in parallel pairs with the passages of one pair crossing those of the other pair in different levels, means in the walls for supporting the ends of conduits in communication through a pair of openings 130

with passages, and a removable cover on the body through which access may be had to the passages.

36. A connecting box comprising a body having openings in its walls disposed in groups, the openings in each side of the box being aligned with similar openings across the box, vertical and horizontal partition walls within the box defining groups of separate passages extending across the box in upper and lower levels, each passage connecting pairs of aligned openings at opposite sides of the box and the box being adapted to have the ends of conduits connected thereto at the openings, whereby conductors in a conduit may be led into the box through an opening, across the box in a passage and into an aligned conduit through an opening aligned with the first opening, and an opening in the horizontal partition wall defining the bottom of each passage in the upper level through which access may be had to a passage in the lower level.

37. A connecting box comprising a body having a flat bottom wall of substantial area and having openings in its side walls disposed in groups, each opening being aligned with a similar opening across the box, partition walls defining passages extending across the box, each passage connecting an opening to its opposed opening, these passages extending in two directions across the box at an angle to each other in different levels, the bottom wall of the box defining the bottoms of certain of the passages, a top wall on the body defining the tops of certain other passages, and a removable cover normally supported on the top wall to close an opening through which access may be had to passages, the tops of which are defined by said top wall.

38. A connecting box comprising a body having a flat bottom wall of substantial area and having openings in its side walls disposed in groups, each opening being aligned with a similar opening across the box, partition walls defining passages extending across the box, each passage connecting an opening to its opposed opening, these passages extending in two directions across the box at an angle to each other in different levels, the bottom wall of the box defining the bottoms of certain of the passages, a top wall on the body defining the tops of certain other passages, and a removable cover normally supported on the top wall to close an opening through which access may be had to passages, the tops of which are defined by said top wall, portions of said partition walls in each of said passages being cut away to afford access through said cover opening to passages not otherwise accessible through said openings.

39. An electrical wiring system for installation in floors which comprises a network of at least double runs of ducts extending in different directions and embedded a substantial distance beneath the surface of the floor, pairs of ducts intersecting other pairs substantially at right angles, and boxes at the intersections, each box having at least two pairs of passages extending across the box and crossing at different levels, each duct leading to the box being in communication through a passage in the box with an aligned duct, whereby a conductor in a duct may be led through the box to the aligned duct while kept separate from conductors in parallel and transversely extending ducts.

In testimony whereof I affix my signature.
EDWARD E. ASHLEY, JR.
